COMBINED STAPLER AND MEMO PAD HOLDER

John J. Olson, St. Paul, Minn., assignor to Brown & Bigelow, St. Paul, Minn.

Application June 9, 1954, Serial No. 30,877

Term of patent 14 years

(Cl. D74—1)

FIG. 1.

FIG. 2.

To all whom it may concern:

Be it known that I, John J. Olson, a citizen of the United States, residing in St. Paul, county of Ramsey, and State of Minnesota, have invented a new, original, and ornamental Design for a Combined Stapler and Memo Pad Holder, for which the following is a specification, reference being had to the accompanying drawings, forming part thereof.

I claim:

The ornamental design for a combined stapler and memo pad holder, as shown.
